[57] CLAIM

The ornamental design for a infant bolster support, as shown and described.

DESCRIPTION

FIG. 1 is a perspective view of an infant bolster support, showing our new design;

FIG. 2 is a side elevational view of the infant bolster support;

FIG. 3 is an end elevational view of the infant bolster support;

FIG. 4 is an opposite end elevational view of the infant bolster support;

FIG. 5 is a top plan view of the infant bolster support; and, FIG. 6 is a bottom plan view of the infant bolster support. The broken line showing of an infant in FIGS. 1 and 2 is for environmental purposes only and forms no part of the claimed design.
